UNITED STATES PATENT OFFICE.

JOHN MENZIES, OF NEW HAVEN, CONNECTICUT.

STEAM BOWL FOR CHEMICAL LABORATORIES.

Application filed May 27, 1922. Serial No. 564,257.

To all whom it may concern:

Be it known that I, JOHN MENZIES, a citizen of the United States, residing at New Haven, in the county of New Haven and State of Connecticut, have invented a new and useful Improvement in Steam Bowls for Chemical Laboratories; and I do hereby declare the following, when taken in connection with the accompanying drawings and the characters of reference marked thereon, to be a full, clear, and exact description of the same, and which said drawings constitute part of this application and represent, in—

Fig. 1 a plan view of my improved steam bowl for chemical laboratories, the slab in which it is mounted being shown as broken away.

Fig. 2 a view thereof in side elevation, with the slab in section.

Fig. 3 a view in horizontal section on the line 3—3 of Fig. 2.

Fig. 4 a detached view, partly in side elevation and partly in section, of the funnel-shaped funnel-mount of the device.

Fig. 5 a view in vertical section of my improved device, with a porcelain funnel positioned in its funnel-mount, a flask being shown by broken lines in the funnel.

Fig. 6 a view corresponding to Fig. 1, showing the device as converted for use as a "hot plate."

Fig. 7 a view in vertical section on the line 7—7 of Fig. 6.

Fig. 8 a detached view, in side elevation, of the removable combined hot-plate and guard.

My invention relates to an improved steam bowl for chemical laboratories, the object being to produce a simple, convenient, durable and efficient piece of laboratory apparatus, constructed with particular reference to avoiding the accumulation of "slop," such as water and chemicals around it upon the laboratory bench, to preventing the leakage of the "slop" through the bench, and the accumulation of corrosive acids in the trap, and to providing for the conversion of the bowl, when not in use as such, into a "hot plate."

With these ends in view, my invention consists in a steam bowl for chemical laboratories, having certain details of construction and combinations of parts as will be hereinafter described and pointed out in the claims.

In carrying out my invention, as herein shown, I employ a one-piece, cast-metal, funnel-shaped funnel-mounting 10 having, at its upper end, an annular assembly flange 11 and formed at its lower end with an externally-threaded sleeve 12. Within its upper edge the said funnel-mount is formed with four regularly-spaced, inwardly-projecting, segmental suspension-lugs 13, separated by drainage-passages 14. The said lugs provide for the suspension in the mount of an ordinary porcelain funnel 15, and the creation of a free, conical drainage-space 16, between the interior surface of the funnel-mount and the exterior surface of the funnel, access to this space 16 being had through the drainage-passages 14 aforesaid. Any water or chemical "slop" which may accumulate from the condensation of vapor or in any other way upon the slab 17 passes downward through this space 16 into the sleeve 12 of the mount 10 and thence into a trap 18, which is formed with an externally-threaded opening 19, adapting it to be screwed directly upon the lower end of the said sleeve.

The flange 11 of the mount 10 fits into a shallow, annular recess 20 in the slab 17, with the upper face of which the upper face of the flange is substantially flush, the said recess 20 being located at the upper end of a conical mounting-opening 21 formed in the slab and corresponding in flare or pitch to that of the funnel-shaped funnel-mount 10. For firmly seating the mount 10 in the slab 17, I employ what I may term a "skeletonized spacer," comprising an upper ring 22 and a lower ring 23, connected by inclined webs or struts 24, the upper ring being considerably larger in diameter than the lower ring. This spacer is passed upward over the lower end of the mount 10, with which it is concentric and is interposed between the lower face of the slab 17, and the upper face of a nut 25 turning on the threaded sleeve 12. When the nut 25 is turned to lift it upon the sleeve 12, the upper ring of the spacer is jammed against the lower face of the slab, with the effect of firmly seating the flange 11 of the mount in the annular recess 20 of the slab. In this manner the mount is firmly positioned in the slab.

The trap 18, aforesaid, has a lateral passage 26 leading out of its bottom, on the level of the floor thereof, into a vertical pas-

sage 27, which, in turn, leads into a lateral, internally-threaded outlet-passage 28 receiving a threaded discharge-pipe 29. The floor of the passage 26 is provided with a clean-out hole 30, normally closed by a plug 31, whereby any acids or heavy sediment not carried off by the flow of the fluid through the trap, may be readily cleaned out. The bottom of the trap is formed with a 10 threaded-opening 32 concentric with its opening 19, for the reception of a feed steam-supply pipe 33 mounting a jet-tube 34, over which the stem of the porcelain funnel 15 is set, the upper end of this tube being 15 plugged and provided with upwardly-inclined perforations, through which the steam jets into the funnel and upon the flask 35 or other vessel set therein.

Under the construction described, the 20 water of condensation or any liquid material that may be spilled on the slab 17 will be immediately carried off through the drainage-spaces 14 and 16, and discharged into the trap 18, thus avoiding all "slop" 25 upon the bench during the conduct of an experiment.

In case it is desired not to use my improved bowl as such, it is only necessary to 30 remove the funnel 15 and replace it by means of a "hot plate," which performs the additional function of a guard in the sense that it prevents the access of small objects, such as corks, stoppers, etc., into the funnel-shaped funnel-mount, since it virtually 35 closes the mouth thereof, though not to the passage of liquids. This combined "hot plate" and guard consists of a disk-like hollow head 36 formed in its edge with drainage-notches 37 and carrying a hollow stem 40 38 corresponding to the shank of the porcelain funnel 15 and passing below the water level of the trap when it replaces the shank of the funnel therein.

I claim:

45 1. In a steam bowl for chemical laboratories, the combination with a slab, of a funnel-shaped funnel-mount, means for fastening the flaring upper end thereof in the said slab, a funnel installed in the said mount, 50 with a clearance-space between it and the same for the escape of superfluous liquids accumulating around the mouth of the mount, a trap mounted upon the lower end of the mount for the reception of such 55 liquids, and a steam tube mounted in the said trap concentric with the said funnel and rising from the trap thereinto.

60 2. In a steam bowl for chemical laboratories, the combination with a slab, of a funnel-shaped funnel-mount set by its upper portion into the said slab, and having its 65 depending-sleeve externally-threaded, a lock-nut mounted upon the said sleeve, a spacer interposed between the nut and the lower face of the slab, whereby the said

mount is firmly seated in the said slab, a funnel installed in the said mount with a clearance-space between it and the same, and a trap mounted upon the said sleeve at a point below the said spacer for receiving fluids escaping through the conical space between the said funnel-shaped funnel-mount and the funnel suspended therein. 70

3. In a steam bowl for chemical laboratories, the combination with a slab, of a funnel-shaped funnel-mount set into the said slab and internally adapted for the clearance-suspension of a funnel therein and provided with an externally-threaded depending sleeve, a lock-nut mounted upon the said sleeve, and a spacer interposed between the said nut and the lower face of the slab, whereby the said mount is firmly seated in the said slab. 75

4. In a steam bowl for chemical laboratories, the combination with a slab, of a funnel-shaped funnel-mount set into the said slab and formed at its upper end with an assembly flange and at its lower end with a threaded sleeve, and adapted within its upper end for the clearance-suspension in it of a porcelain funnel; a nut mounted upon the said sleeve, and a skeletonized, flaring spacer interposed between the said spacer and slab for firmly seating the said mount 80 85 90 95 therein.

5. In a steam bowl for chemical laboratories, the combination with a slab, of a funnel-shaped funnel-mount set by its upper portion into the said slab and having a depending, externally-threaded sleeve, a funnel located in the said mount, means for the clearance-suspension of the said funnel in the said mount for the creation and maintenance of a conical space between them, a trap mounted upon the depending threaded sleeve of the mount for receiving the fluids draining from the slab through the said 100 105 conical space between the mount and funnel, and a steam tube rising into the funnel. 110

6. In a steam bowl for chemical laboratories, the combination with a slab, of a funnel-shaped funnel-mount having its flaring upper end located therein, means applied to the mount and engaging with the lower face of the slab for holding it firmly in place, a funnel suspended in the said mount concentric therewith, with a clearance space between it and the same, a trap mounted upon the lower portion of the mount and receiving liquids discharged thereinto, and a steam tube mounted in the trap concentric with the funnel and extending upward thereinto, the said trap having a lateral passage leading out of its bottom into a vertical passage opening into a passage receiving a discharge-pipe. 115 120 125

7. In a steam bowl for chemical laboratories, the combination with a slab, of a funnel-shaped funnel-mount having its flaring 130

upper end set into the said slab and having its depending sleeve externally-threaded, a lock-nut mounted upon the said sleeve, a spacer interposed between the lower face of 5 the slab and the said nut, whereby the mount is firmly held in the slab, a funnel located in the said mount concentric therewith, with a clearance-space between it and the same, a trap mounted upon the threaded lower 10 end of the said mount for the reception of liquids escaping into the said clearance space from the top of the slab, a steam-pipe mounted in the trap concentric with the funnel and rising thereinto, and a combined hot-plate 15 and guard consisting of a head and a tubular shank, the former being adapted to substantially occupy the upper end of the funnel and the latter being adapted to pass downward over the steam-tube into the trap. 20 8. In a steam bowl for chemical labora-

tories, the combination with a slab, of a funnel-shaped funnel-mount, means for firmly seating the same in the slab, a trap applied to the projecting lower end of the said mount, a steam-tube rising from the said 25 trap, and a combined "hot plate" and guard consisting of a hollow disk-shaped head and a depending tubular shank, the said head being formed in its edge with drainage-notches into which liquids accumulating 30 upon the slab are discharged into the concentric space between the mount and funnel and thence into the trap.

In testimony whereof, I have signed this specification in the presence of two subscribers. 35
